ARCHER'S SIGHT

Bert E. Fredrickson, Green Bay, Wis.

Application October 31, 1947, Serial No. 783,339

8 Claims. (Cl. 33—46)

1

My invention relates to sights for archers' bows, and more particularly to such sights as are adapted to be mounted on a long bow to improve the accuracy of the archer.

With the foregoing in view, an object of my invention is to provide an improved sight for archers' long bows.

A further object is to provide an improved sight for long bows, which sight is adjustable vertically on the bow for increased or decreased ranges, and which sight is simultaneously tilted longitudinally whereby to enable an archer to align the same with a target without varying his normal position of head or eyes to compensate for the increased or decreased angle of the bow.

A further object of the invention is to provide an improved sight for long bows which includes a novel sighting means and a reticle.

A further object is to provide an improved sight for long bows which includes a novel combination of sighting means and a reticle with novel means for adjusting said sight vertically for varying ranges and simultaneously imparting a tilt to the sight to compensate for the resultant variance in the angles of the bow.

A further object is to provide an improved sight for long bows which is adjustable vertically on the bow for varying ranges and simultaneously tiltable to compensate for the resultant variance in the angles of the bow, and a single means for simultaneously adjusting and tilting the sight.

Other objects and advantages reside in the particular structure of the invention, combination and arrangement of the several parts thereof, and in the particular mode of operation, all of which will be readily apparent to those skilled in the art upon reference to the attached drawings in connection with the following specification, wherein the invention is shown, described and claimed.

In the drawings:

Figure 1 is an elevation of a preferred form of the sight, a long bow being shown fragmentarily in elevation;

Figure 2 is a front view of Figure 1;

Figure 3 is a longitudinal vertical section taken substantially on the plane of the line 3—3 of Figure 2;

Figure 4 is a longitudinal vertical section taken substantially on the plane of the line 4—4 of Figure 2;

Figure 5 is a horizontal section taken substantially on the planes of the line 5—5 of Figure 1;

Figure 6 is a longitudinal vertical section through the base taken substantially on the plane of the line 6—6 of Figure 10;

2

Figure 7 is a fragmentary rear end view of a detail of the invention;

Figure 8 is an elevation like Figure 1, but taken from the opposite side of the device;

Figure 9 is an enlarged fragmentary longitudinal section showing a detail;

Figure 10 is a plan view of the sight apart from the rest of the structure.

Referring specifically to the drawings, wherein like reference characters have been used throughout to designate like parts, 10 designates a long bow of any suitable or usual form having a hand grip 11 intermediate the ends thereof. The sight according to my invention comprises generally a mount 12 and a sight base 13 vertically and tiltably adjustable relative to the mount.

Referring first to the mount 12, the same comprises a collar member of generally rectangular shape having a rear wall 14, side walls 15 and 16, and a front wall 17. Such collar is adapted to fit substantially loosely over the bow 10 and is adapted to be clamped thereto by any suitable clamp means, such as the clamps 18 and 19, which adjustably clamp the rear and one side of the bow 10 and which are actuated by any suitable adjustable clamping means, such as the machine screws 20 which are extended respectively through the rear wall 14 and side wall 16. The collar aforesaid is intended to be mounted on the bow, as shown, a short distance above the hand grip 11. Obviously, the collar is adjustable longitudinally of the bow 10 to fit the individual archer, and thereafter requires no further adjustment.

The front wall 17 of the mount 12 comprises a rear wall for a housing 21 in which is mounted the actuating means for adjusting the sight. The housing 21 is substantially rectangular and includes side walls 22 and 24, a top wall 23 and a forward wall 24. A shaft 25 is journaled between the side walls 22 and 24, and one end 25' is preferably of non-circular configuration and extends outwardly of the side wall 22 for a purpose to be described. A sight-setting dial 26 is fixed on the outer surface of the side wall 22

and the shaft 25 extends therethrough with the squared end 25' axially outwardly thereof. A pointer 27 is fixed on the shaft end 25' and indicates the setting of the sight by means of appropriate indicia formed and inscribed on the surface of the dial 26. A stop 28 at one extremity of the series of indicia serves to engage the pointer 27 and limit rotation of the same in both directions.

The shaft 25 has fixed thereon for rotation therewith a pair of laterally-spaced spur gears 29 and 30. Each spur gear is adjacent the inner

surface of one of the walls 22 and 24 of the housing 21. The spur gears 29 and 30 are of unequal ratios for a purpose to be described later. For instance, the spur gear 30 may be of 32 pitch and have 26 teeth. In like manner, the spur gear 29 may be of 32 pitch and have 22 teeth. The shaft 25 also has fixed thereon for rotation therewith a ratchet gear 31 which in the form shown is intermediate the gears 29 and 30 and spaced therefrom.

A ratchet lever 32 is formed with a pair of bifurcated legs 33 at one end thereof which are journaled to the shaft 25 on either side of the ratchet gear 31. The lever 32 is preferably of tubular or channel configuration. Referring specifically to Figure 9, the legs 33 of the ratchet lever have journaled therebetween by a suitable pin 37 a double-arm pawl 36. A pawl-actuating slide 35 is slidable within the channel portion 34 of the ratchet lever 32. A bell crank 39 is also journaled between the legs 33 by a suitable pin 40. The bell crank 39 is formed with arms 41 and 42 and the arm 42 thereof has pivoted thereto one end of a link 43, the other end of which is fixed to the slide 35. The slide 35 may be formed with a knurled boss 44 to facilitate the actuation thereof. The pawl 36 is formed with a hollow stem 38 which receives one end of a pin 45 which is headed at the other end to provide a seat for a coil spring 46. The other end of the coil spring 46 seats around the stem 38 against the pawl 36. The free end of the head of the pin 45 is selectively seatable on one of the arms 41 or 42 of the bell crank 39 and comprises means of shifting or reversing the pawl 36. As shown in Figure 9, the slide 35 has been slid toward the ratchet gear 31, whereby the head of the pin 45 is seated on the bell crank arm 41. In this position, when the lever 32 is moved in a counter-clockwise direction, the ratchet gear 31 will be likewise moved in a counter-clockwise direction. However, when the slide 35 is slid downwardly, Figure 9, the link 43 will pull the bell crank 39 to the Figure 1 position, whereby the headed stem 45 is shifted to the bell crank arm 42, whereby to engage the opposite tooth of the pawl 36 with the ratchet gear 31. In this position, movement of the lever 32 in a clockwise direction will drive the ratchet gear 31 in a clockwise direction. To effect the movement of the gear 31 in either direction, it is merely necessary to impart a limited rotary movement to the lever 32, whereupon the pawl 36 is brought out of engagement with the gear 31 and the lever 32 returned to its original position. The pawl 36 is then brought into engagement with the gear 31, and the lever 32 is once again moved through its path of rotary movement.

A pair of laterally-spaced racks 48 and 47 are vertically slidable in the housing 21 in slideways 49. Both of the racks are of a like pitch, as the gears 29 and 30, and are in mesh therewith. In view of the fact that the gear 30 has more teeth than the gear 29, it is obvious that, as the shaft 25 is rotated one complete revolution, the rack 47 in mesh with the gear 30 will be projected further upwardly or downwardly than is the rack 48 which is in mesh with the smaller gear 29. Thus, to raise or lower the sight per se, to be described later, it is only necessary to shift the slide 35 to an appropriate position in the lever 32 and swing the lever forwardly and backwardly to rotate the shaft 25. If desired, the spring 99 may be secured to the rear wall 17 of the housing 21 with its free end in engagement with the

lever 32 to load the latter to a forward position.

The upper end of the rack 47 is formed with an integral extension 50 having a free end 52 which is pivoted in the forward end of the sight base 13. In like manner, the upper end of the rack 48 is provided with an integral extension 51 having a free end 53 which is pivoted to the rear end of the sight base 13. Thus, as the racks 47 and 48 are extended in vertical directions, they carry with them the base 13, while at the same time, by virtue of the unequal projection of the racks, the base 13 will be tilted for a purpose to be described later. In this connection, it is noted that inasmuch as the smaller gear 29 and rack 15 48 are connected to the rear end of the base 13, the rear end will move vertically in both directions to a smaller degree than will the front end of the base.

The sight base 13 comprises a base portion 54 in which the ends 52 and 53 of the rack extensions 50 and 51 are journaled. The base portion 54 is provided with a central longitudinally-extending recess 56. The free end 53 of the rack extension 51 is journaled across the rear end of such recess 56 and such free end 53 has fixed thereto one end of a link 58, a lug 57. The lug 57 has fixed therein in any suitable manner one end of an arm 59. The opposite end of the arm 30 59 is upwardly offset for a purpose to be described later. Thus, as the free end 53 is rotated relative to the base portion 54, the arm 59 and the free end 60 thereof will be swung vertically relative to the base portion 54. The forward end of the base 35 portion 54 has fixed thereon intermediate the sides thereof an upstanding pin 61.

A sight bar 55 is seated atop the base portion 54 and pivoted thereto by a vertical pivot of any suitable character, such as the thumb screw 62. The under surface of the sight bar 55 is suitably recessed, as at 63 and 64, to receive the offset free end 60 of the arm 59 and the pin 61, respectively. The sight bar 55 in the region of the recess 64 is provided with transversely inwardly-extending threaded bolts or the like 65, Figure 2, the inner ends of which are adapted to bear against the pin 61 to provide means for moving the front end of the sight laterally on the pivot 62. The sight bar 55 has fixed therein between the recesses 64 and 63 a longitudinally-extending pivot pin 66 which freely mounts a base of a pointer 67 for a dial 68. The free end 60 of the arm 59 is journaled in the base portion of the pointer 67 laterally of the pivot 66, Figure 10. Thus, as the arm 55 is raised or lowered, the pointer 67 is swung about its pivot 66. The forward face of the dial is formed and inscribed with suitable sight-setting indicia which are arranged as "mirror writing," whereby a reflection of the indicia will 60 read as normal indicia from left to right. Accordingly the archer can correlate the various positions of the arm 55 as it is raised or lowered with a corresponding one of the numerical indicia forming the dial 68.

Forwardly of the dial 68, the sight bar 55 carries a substantially vertically-extending front sight 69 which includes a partially transparent reflector 70. The partially transparent reflector 70 may be slightly concavo-convex with the concave surface thereof facing rearwardly, whereby to slightly enlarge any reflections in such partially transparent reflector. Moreover, the partially transparent reflector 70, while transparent, is preferably slightly tinted or coated, whereby to 75 have slight reflecting characteristics.

The rear end of the upper surface of the sight bar 55 has attached thereto in any suitable manner a reticle means 71 which includes a prism 72 having a substantially horizontal face 73, a substantially vertical face 74, and a rear face 75 which connects the front and bottom faces at angles of substantially 45°. The bottom face 73 is formed and inscribed with suitable reticle-providing indicia which may comprise a dot 76, a cross-hair 77, and a pair of dots 78 on the horizontal arm of the cross-hair 77 on either side of the vertical arm thereof. As is seen in Figure 7, when the archer looks through the front sight reflector 79, he will see faintly reflected therein the reticle indicia 76, 77 and 78, which are reflected forwardly off of the rear face 75 of the prism 72. The archer will also see a reflection of the dial 68 and indicator hand 67 therefor. It should be noted at this time that the front sight 69 and the reticle means 71 do not preferably extend exactly vertically from the sight bar 55. As is clearly shown in Figure 1, both the front sight 69 and the front face 74 of the prism 72 are inclined rearwardly slightly from a right angle with the upper surface of the sight bar 55. This is necessary in the front sight to provide an angle of reflection with the rear surface of the front sight 69 equal to an angle of incidence aligned with the archer's eye and in the prism to project the reflected rays through the front face 74 thereof at an angle thereto. In this connection it should be noted that the reticle is located on the principal point of focus of the partially transparent reflector 79 whereby a sharply focused reflection is seen by the archer at all times in the normal use of the device.

The front sight and reticle 69 and 71 are used as follows: The archer centers the reflection of one of the reticle indicia 76, 77, or 78 in the front reflector 79. To facilitate this, the front reflector may be provided with cross-hairs, not shown. The purpose of having a plurality of reticle indicia is to permit the archer to make rapid compensations in a given sight setting without pausing to re-set the sight. This is particularly important when the archer is actually hunting game with a bow and arrow. Thus, a dot 76, when centered in the front reflector 79, may indicate a range corresponding to the setting of the hand 67 on dial 68. In like manner, the cross-hair 77, which may be simultaneously seen in the reflector 79, may indicate when centered in the partially transparent reflector 79 an increased range of say thirty or forty yards. The dots 78 indicate lateral leads for the cross-hair 77 when either of those dots is centered in the reflector 79. Such lateral leads are particularly important when the archer wishes to allow for wind, or when shooting at running game, and will be readily understood by those skilled in the art.

An important feature of the invention comprises the provision whereby as the sight base 13 is adjusted vertically relative to the bow, it is tilted simultaneously. It is important in archery that the nock, or rear end of the arrow, be held at the same point prior to a shot. This point is usually just beneath the chin of the archer. However, as the bow is raised to increase the range, there is an obvious tendency to tilt the head backwardly, and if a sight is not tiltable, at extreme ranges, it will be impossible to view the target through the sight. In the sight disclosed, as range is increased, the sight bar is lowered along the bow 10, and at the same time the front end is tilted downwardly so that it maintains a sub-

stantially horizontal position irrespective of whether the bow is tilted upwardly or downwardly. Thus, the sight will remain aligned with the target irrespective of the elevation or depression utilized in sighting. Moreover, this tilting provision of the sight permits the archer to sight through it without craning his neck or otherwise moving his head from its accustomed position. Obviously, this provision of the sight makes for extremely greater accuracy in shooting by permitting uniformity of sighting and shooting actions of the archer irrespective of the range.

While I have shown and described what is now thought to be a preferred embodiment of the invention, it is to be understood that the same is susceptible of other forms and expressions. Consequently, I do not limit myself to the precise structure shown and described hereinabove except as hereinafter claimed.

20 I claim:

1. A sight for an archer's bow, comprising an elongated base having a front and a rear end, means for attaching said base to said bow transversely thereof, a front sight carried by said front end of said base, reticle means carried by said rear end of said base, said means for attaching said base to said bow including separate horizontally-disposed pivot means mounting said front and rear ends of said base, means for adjusting said base, said last-named means comprising a single adjusting means for adjusting said base vertically and simultaneously tilting said base on said pivot means, said front sight comprising a substantially vertically-disposed partially transparent reflector, and means for reflecting an image of said reticle onto said reflector, a sight-setting indicator carried by said base between said front sight and said reticle, and means operatively coupling said indicator to said adjusting means whereby to actuate said indicator simultaneously with the vertical adjustment of said base.

2. A sight for an archer's bow, comprising an elongated base having a front and a rear end, means for attaching said base to said bow transversely thereof, front sight carried by said front end of said base, reticle means carried by said rear end of said base, said means for attaching said base to said bow including separate horizontally-disposed pivot means mounting said front and rear ends of said base, means for adjusting said base, said last-named means comprising a single adjusting means for adjusting said base vertically and simultaneously tilting said base on said pivot means, said front sight comprising a substantially vertically-disposed partially transparent reflector, means for reflecting an image of said reticle onto said reflector, a sight-setting indicator carried by said base between said front sight and said reticle, means operatively coupling said indicator to said adjusting means whereby to actuate said indicator simultaneously with the vertical adjustment of said base, and said indicator being forwardly directed and reflectable in said front sight.

3. A sight for an archer's bow, comprising an elongated base having a front end and a rear end, a front sight and a reticle carried respectively by said front and rear ends of said base, a mount for said base, means for detachably connecting said mount to said bow, a shaft rotatable in said mount, a pair of spaced gears of unequal ratios fixed on said shaft, a pair of racks slidable in said mount, there being a rack in operative engagement with each gear, means for rotating said shaft in both directions, and means pivotal-

ly connecting each rack to an opposite end of said base whereby rotation of said shaft in either direction projects said racks unequally in like directions.

4. A sight for an archer's bow, comprising an elongated base having a front end and a rear end, a front sight and a reticle carried respectively by said front and rear ends of said base, a mount for said base, means for detachably connecting said mount to said bow, a substantially horizontally-disposed shaft rotatable in said mount, a pair of spaced gears of unequal ratios fixed on said shaft, a pair of substantially vertically-disposed racks slidable in said mount, there being a rack in operative engagement with each gear, means for rotating said shaft in both directions, and means pivotally connecting each rack to an opposite end of said base whereby rotation of said shaft in either direction projects said racks unequally in like directions.

5. A sight for an archer's bow, comprising an elongated base having a front and a rear end, a front sight and a reticle carried respectively by said front and rear ends of said base, a mount for said base, means for detachably connecting said mount to said bow, a substantially horizontally-disposed shaft rotatable in said mount, a pair of spaced gears of unequal ratios fixed on said shaft, a pair of substantially vertically-disposed racks slidable in said mount, there being a rack in operative engagement with each gear, a third gear fixed on said shaft, a lever pivotally mounted in said mount, a reversible pawl carried by said lever and normally engaging said third gear to rotate said shaft in one direction, means for reversing said pawl to engage said third gear to rotate said shaft in the opposite direction, and means pivotally connecting each rack to an opposite end of said base whereby rotation of said shaft in either direction projects said racks unequally in like directions.

6. A sight for an archer's bow, comprising an elongated base having a front and a rear end, a front sight and a reticle carried respectively by said front and rear ends of said base, a mount for said base, means for detachably connecting said mount to said bow, a pair of base-adjusting means carried by said mount, mount-carried rotatable means for simultaneously adjusting said base-adjusting means unequally in like vertical directions, means pivotally connecting one of said base-adjusting means to the front end of said base, and means pivotally connecting the

other of said base-adjusting means to said rear end of said base.

7. A sight for an archer's bow, comprising an elongated base having a front end and a rear end, a front sight and a reticle carried respectively by said front and rear ends of said base, a mount for said base, means for detachably connecting said mount to said bow, a base-adjusting member carried by said mount, means pivotally connecting said member to said front end of said base, a second base-adjusting member carried by said mount, means pivotally connecting said second member to said rear end of said base, a rotatable means carried by said mount, means operatively connecting said rotatable means to both of said members, and said last-named means including means operative upon rotation of said rotatable means to adjust said first member vertically at a given ratio and simultaneously adjust said second member vertically in the same direction at a lesser ratio.

8. A sight for an archer's bow, comprising an elongated base having a front end and a rear end, a front sight and a reticle carried respectively by said front and rear ends of said base, a mount for said base, means for detachably connecting said mount to said bow, a pair of base-adjusting means carried by said mount, mount-carried means for simultaneously adjusting said base-adjusting means unequally in like vertical directions, means pivotally connecting one of said base-adjusting means to said front end of said base, and means pivotally connecting the other of said base-adjusting means to said rear end of said base.
